US00D864152S

(12) **United States Design Patent** (10) **Patent No.:** **US D864,152 S**
Liu (45) **Date of Patent:** **** Oct. 22, 2019**

(54) **HEADPHONE**

(71) Applicant: **Baihua Liu**, Guangdong (CN)
(72) Inventor: **Baihua Liu**, Guangdong (CN)
(73) Assignee: **Shenzhen Wonderhug Electronics Co., Ltd**, Shenzhen, Guangdong (CN)

(**) Term: **15 Years**

(21) Appl. No.: **29/634,805**

(22) Filed: **Jan. 25, 2018**

(51) LOC (12) Cl. **14-01**
(52) U.S. Cl. **USPC** **D14/205**

(58) **Field of Classification Search**

USPC D14/205, 223, 188, 192; D29/112; 2/209; 181/129, 130, 135; 379/430, 431; 381/380, 381, 374; 455/90.3, 575.1, 455/569.1

CLAIM

The ornamental design for a headphone, as shown and described.

DESCRIPTION

FIG. 1 is a perspective view of a headphone showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict environment that forms no part of the claimed design.

1 Claim, 7 Drawing Sheets
